RING RESAWING MACHINE

Joseph H. Hoern, Saginaw, Mich., assignor to
Wilcox-Rich Corporation

Application April 2, 1930. Serial No. 441,091

7 Claims. (Cl. 90—15)

This invention relates to a ring re-sawing machine of that "automatic" type in which a turret table, preferably inclined, is provided with means for its intermittent rotative advance and with means for holding both said table and a ring which is presented for sawing against displacement; but novel ring-holding means, preferably pneumatic, are herein made subject to a remote and automatic synchronizing control.

Although the form and dimensions of the clearance gap in piston rings is recognized to be a matter of importance, and the general purposes of re-sawing piston rings before or after finishing operations are well known, reference may be made to one specific organization employing a turret in connection with the operations referred to, such being described and claimed in my co-pending application, Serial No. 389,661, filed August 31st, 1929. In some of its aspects the present invention might be referred to as an improvement upon that of the mentioned application,—as in its provision of novel means to assure a correct positioning, a clamping and an ejection of rings, and also in its provision of special curvature-determining and ring-ejecting devices capable of use either with or separately from any pneumatic clamp; but the present organization contemplates translational movement of a comparatively light saw or milling cutter, preferably secured in a dependent frame, rather than an advance and retraction of the heavy turret, to effect each sawing operation; and also the use of special means for establishing desired timing relationships between all necessary operations; and it will accordingly be completely described without further reference to the mentioned pending case.

Other objects of the present invention may be best appreciated from the following description of an illustrative embodiment thereof, taken in connection with the appended claims and the accompanying drawings, and intended to be so complete as to obviate need of further reference to the mentioned pending case.

Fig. 1 is a side elevational view, with air-control conduits cut away.

Fig. 2 is a corresponding top plan view, with turret parts broken away.

Fig. 3 is a front or end elevational view, taken as if from the position of an operative at the left of Fig. 1.

Fig. 4 is a vertical sectional view, taken substantially as suggested by the broken line 4—4 of Fig. 1.

Fig. 5 is a sectional view, taken substantially

as suggested by the inclined line 5—5 of Fig. 3, and the line 5—5 of Fig. 7, but with parts broken away to different levels.

Figs. 6 and 7 respectively are sectional views taken substantially as suggested by the lines 6—6 and 7—7 of Fig. 5.

Figs. 8, 9, 10 and 11 are respectively detail sectional views taken substantially as suggested by lines correspondingly numbered upon Fig. 7.

Fig. 12 is a diagrammatic detail view taken substantially as suggested by line 12—12 of Fig. 1.

Fig. 13 is a view corresponding to Fig. 5, but showing an alternative construction.

Figs. 14 and 15 are partial sections on lines 14—14 and 15—15 of Fig. 13.

As to the general features of the organization selected for present description, Figs. 1, 2 and 3 will be seen to disclose, upon a main base element B, an inclined turret organization T; the table thereof may be intermittently rotated from a remote motor M through a main drive shaft DS and a worm and worm gear W, W'; and the illustrated transmission includes also fore-and-aft shafts FS and AS between which is interposed a housed Geneva gear G. A main frame MF on the base B supports also an elevated bracket EB from which is swung a pendent frame PF for a saw or cutter S,—this being preferably advanced by a spring SP and retracted by means of a lever L and a longitudinally movable link AL. The saw S may be driven from the motor M through a belt transmission system comprising pulleys P, P' and PU, PU',—the latter pair being respectively carried by a fixed or other upper shaft US and a saw shaft SS mounted on the pendent frame PF, and additional pulleys PL, PL' being used to transmit motion between parallel shafts MS and DS. A system comprising a compressed air control cylinder AC and a clamp control-cylinder CC may provide interdependent means for manipulating, at suitable times with reference to the movements of the table of the turret organization T and the saw S, a ring-clamping device RC,—the latter being shown as carried by a yoke Y; and a cam C on shaft AS may control parts of a locking device for the rotatable table of turret T; but details of the mentioned devices and of various auxiliary means will obviously require separate description.

The shafts DS and AS (each being provided with any desired bearings additional to those shown) may each contain a reducing and/or flexible coupling 20; and the mentioned Geneva gear G is shown as including a wrist pin 22 adapt-

ed to enter, at suitably timed intervals, slots 23 in a terminal plate 24 on shaft FS. This shaft is shown as provided with a bearing 25, secured to the main frame MF; and the mentioned cam C, 5 upon shaft AS, is shown as engaging a roller 26 upon one end of a lever 27. This may be pivoted, as at 28, within a fixed base portion 29 of the mentioned turret organization, and employed to operate the indexing device.

10 Referring now to Fig. 5 for a general disclosure of the turret organization T, the lever 27 is shown as provided with a laterally extending cam pin 30. This pin, or a hardened sleeve or roller 31 thereon, is intended accurately to fit within a cam slot 32, provided in a slidable element or bolt 33, shown as extending through a sleeve 34 and as terminating in a conical head 35. A downwardly extending portion 36 of bolt 33 is shown as guided by an opening 37 provided in the fixed 15 base 29; and a compression spring 38 is shown as interposed between said base and a shoulder 39 upon the slidable element 33 in such manner as to bias the latter toward an upward position,—adapting it to cooperate with any one of a plurality of conical or other socket elements 40. These may be provided in the mentioned table 41 20 of the turret organization T to receive bolt 33 wherever the position of cam C on the constantly rotated shaft AS permits. The table 41 is shown as provided near its edge with bearings 42 and as centrally provided with an apertured boss within which is secured a central shaft 43, provided with a shouldered collar 44 opposite said boss. A downwardly extending portion 43' of 25 this shaft may carry not only upper sets of bearings 45 and 46 and a lower set of bearings 47 (the bearings 45 and 47 being shown as respectively received in cups 48 and 49 provided in horizontal webs 50 and 51 integral with the fixed base 29) but also a bevelled gear 52 engaging a corresponding gear 53, upon the forward end of the intermittently rotated shaft FS,—provided with any suitable bearings 54; and it will be understood that not only the advance and retraction 30 of the bolt 33 but also the advance and retraction of the saw S, or its equivalent, are intended to be effected during intervals of rest of the table 41.

Referring now more particularly to ring-handling features well shown in Figs. 5-10, the 50 table 41 is shown as provided with four chucks or ring-receiving elements 55, of such configuration that rings R may be dropped or sprung therein and retained by any suitable clamping means provided therefor at a cutting station CS,—this 55 being shown as diametrically opposite a loading station LS. In the illustrated embodiment, a clamping element 56 of the ring clamping device RC is shown as connected with a plunger organization 57 by means of a rod 58 and a ball-and-socket joint 59,—the ball thereof being retained by means of a plate 60 and screws 61. To assure a proper positioning and configuration of the rings R during advance and retraction of the saw S, or its equivalent, receiving elements 55 may be 60 provided not only with interruptions, permitting the advance of the saw, but with the inclined or other special surfaces 62 suitable for engagement by adjusting means such as screws 63 (see Figs. 7 and 8) whereby a predetermined configuration 65 may be imparted to the receiving elements 55; and the configuration of the clamping element 56, whether advanced by hydraulic or other means, may be such as positively or resiliently to conform 70 to the inserted ring R to the receiving element 55.

75 Assuming the rings R have been previously

sawed, in order to provide for the insertion thereof in a desired relationship to the plane of advance of the saw S, means such as a thin tongue-like member 64, radially and slidably mounted for advance and retraction to and from or in the plane of the rings R, may be provided; and, in Figs. 5, 80 7, 9 and 10, said tongue-like member is shown as carried by a slidable element 65 (which may be held down by plates engaging flanges thereon) having a transverse slot 66 suitable for engagement by a cam element such as a pin 67 upon an arm 68. A limited rotational movement may be imparted thereto, at suitable times (and in opposition to a spring 68a surrounding a short shaft 68b, and secured on a guide 68c) by means such as a cam finger 69, adapted to engage a cooperating fixed cam element 70,—shown as carried by a mentioned web 50. It will be understood that during an interval of rest at the loading station LS, the tongue 64 is intended to occupy an outer position, such as that in which it is shown at the right of Fig. 7, in order to pre-determine the position of the slot in any ring there inserted by manual or other means; but that, preferably before the step-by-step rotation of the table 41: 100 brings a ring to rest at the station CS, the tongue 64 is retracted; and that either manual or automatic means may be employed to eject the successive rings R at an unloading or ejection station ES after the completion of a sawing or resawing operation. Automatically and reliably to effect a lifting of rings at this station (within easy reach of an operative assumed to sit or stand opposite the loading station LS) additional cam-operated means, including a slidable element 71 110 (vertically movable against the action of a spring 71a by a suitable cam 71b therebelow) and a pin 72, extending beneath a ring R, may be employed; and it will be understood that the device last referred to may be duplicated, if desired, at opposite 115 points in the circumference of the respective rings, and also that the interposition of an arm 71' between elements 71 and 72 enables the radial position of the latter to be adapted to larger or 120 smaller rings.

In order to permit some resilient response of the clamping element 56 to any special configuration that may have been given to the ring-receiving element 55, and to bring any ring therein to a like configuration, it is suggested, in Figs. 6 and 7, that the clamping element 56 be provided with arcuate kerfs or slots 73, shown as extending about a quadrant's distance on each side of a saw-receiving notch 74; and it will have been noted that the plunger organization 57 is so disposed within a mentioned cylinder CC and so constructed as to permit pneumatic or other hydraulic manipulation of the clamping element 56 through the rod 58. As best shown in Fig. 3, the cylinder CC may be directly supported from the stationary yoke Y, extending over the cutting station CS; the plunger organization 57 may include a leather or other cupped element 75, providing a fluid-receiving chamber 76 thereabove; an interior guide 77 for the rod 58 may be surrounded by a clamp-retracting spring 78; the cupped element 75 may be retained between a plate 79, engaged by said spring, and a cooperating plate 80, shown as retained by a nut 81, upon the end of the rod 58; and air or other fluid may be admitted to the chamber 76 and permitted to exit therefrom, at suitable times, by either manual or automatic means,—the latter being preferred. Inadvertent rotational displacement of the clamping elements 56 may be obviated by any desired means,—such 150

as the slidable engagement of a finger 81a within a socket element 81b.

Returning now to Figs. 1, 2 and 4, properly to manipulate the saw S, the link AL is shown as 5 adjustable by means comprising a turnbuckle element 82, interposed between threaded members 83 and 84, these latter being respectively connected to the pendent frame PF and the lever L by pivot pins 85 and 86; and said lever is shown as 10 hung from an arm 87 by means of an additional pivot pin 88. The pendent frame PF is shown as hung from the upper shaft US, extending through clamping elements 89 on the elevated bracket EB, by bearing organizations 90 and 91; and said 15 pendent frame may include, at its lower end, a barrel or bored-out portion 92, adapted to receive bearings 93 and 94 for the saw shaft SS,—these latter being shown as respectively held in place between the shoulder 95 and a plate 96 (carrying 20 a gland organization 97, adjacent the pulley PU') and an additional shoulder 98 with which a plate 99 (carrying a gland organization 100) cooperates. Any usual or desired means may be employed to hold the milling cutter or saw S in its 25 indicated position upon the shaft SS; and the pendent frame may be advanced at suitably timed intervals when the table 41 is at rest, by means such as the mentioned spring SP. This is shown as housed within a casing 101 which 30 may provide or contain a stop 102 therefor and may receive also a slidable element 103, connected with the pendent frame PF by a rod 104,—which may be pivotally secured at its respective ends to said frame and to said slidable element.

35 The lever L is preferably provided with means which act positively at least in the timely retraction thereof. For this purpose, a cam roller 105, provided upon the lower portion thereof, may be engaged by a cam 106, secured upon the shaft AS; 40 and, to assure admission and exhaust of air or another operating fluid, at suitably timed intervals, to and from the chamber 76 of the described clamping organization, a valve organization including the mentioned cylinder AC and a valve- 45 controlling longitudinally movable rod 107, shown as connected by a pivot 108 with an extension 109 upon the lever L, may be employed. The cylinder AC is shown as provided with an air inlet pipe 110 and an air outlet pipe 111 and also with pipes 112 and 113 respectively leading to and from openings 114 and 115 in the cylinder CC of the clamping organization.

The air cylinder AC may be pivotally supported, as at 116, upon a post 117; and the adjustable link 50 AL has been referred to as serving positively to retract the pendent frame PF and the saw S. Frame PF and the lever L being related substantially as parallel links, it may be regarded as comparatively immaterial whether saw-advancing pressure is applied to the former (as by means 55 of spring SP) or to the latter, the remote timing of the operation of clamping device RC being, in any case, preferably effected by valve-operating means directly or indirectly connected with 60 one of said links. For example, as suggested in Figs. 1 and 12, rod 107 may be connected or integral with a valve element 118, for movement in response to requirements of the saw-retracting cam 106, or its equivalent. It will be understood 65 that, when this construction is employed, each rotation of cam 106 produces not only a withdrawal of saw S but such an inward movement of 70 valve 118, upon said withdrawal, as to release clamp RC by an outflow through a passage 119— 75 in readiness for an advance of the turret table;

and an outward movement of valve 118, as effected by the action of spring SP on frame PF after said table comes to rest while a low portion of the cam 106 engages the cam roller 105 attached to the lever L, brings passage 120 of the valve into register with the air-inlet 110 and the lead line 112 to the clamp RC,—which is thereupon actuated to clamp the next ring in advance of its engagement by the saw S.

Parts similar to those above referred to are 80 designated by like characters with an added "a" in the disclosure of an alternative form in Figs. 13, 14 and 15; but bevel-tipped locating tongues 64a are shown as movable to and from the planes of rings R' by levers 65a,—actuated by pins 67a in 85 opposition to springs 62a'. Said levers may be retained beneath plates 121a by means such as blocks 122a carrying pivots 123a and secured by separate screws 124a. The tongues 64a may enter ring slots to any desired extent; and it is suggested in Figs. 14 and 15 that tongues 64a be 90 retained on levers 65a by means such as angle blocks 124a' and screws 125a. Fig. 14 shows not only a cam 70a for the elevation of pins 67a at 95 station LS but a plurality of cams 71b, 71b' for the simultaneous lifting of oppositely disposed ring-ejecting pins 72a, 72a' at ejection station ES.

The mode of operation of the various interdependent mechanisms of the present re-sawing 100 machine having been indicated in connection with the description thereof, it will be understood that rings are placed in the respective chucks on the intermittently advanced table 41 at the loading station LS,—automatic means being 105 there provided to assure the advance of each locating tongue in such manner as to assure a desired orientation of the rings; and that, after leaving this station, each tongue is retracted (by means including a spring 68a or 68a') before a 110 ring is clamped (in any desired configuration, and during a pause at the cutting station CS) by any pneumatic or other ring-clamping device RC provided upon the stationary yoke Y,—the upper end 35 of the bolt 33 of the indexing device being 115 meantime seated in a socket 40. Each ring being thus held sprung to a desired configuration, by the chuck and the rigid or resilient parts of the 120 movable clamping member (in order to assure a predetermined angular relationship between the 125 cut surfaces) the saw S is then advanced and retracted; the clamp is automatically released (as by the controlled escape of the operating fluid through the pipes 113 and 111) and the bolt 33 is 130 withdrawn before any additional movement is imparted to the table 41, or its equivalent; and said additional movement is incidentally effective to 135 eject the mentioned ring at the station ES and to bring an empty chuck opposite the loading station LS.

Although the foregoing description has included 140 complete details of but a single embodiment of the present invention, it should be understood not only that various features thereof might be independently used, but also that numerous modifications, additional to any suggested herein, might easily be devised by workers informed of the foregoing,—all without departure from the scope 145 of the present invention as the same is indicated in the following claims.

I claim:

1. A ring re-sawing machine including, in combination, a saw suspended for rotatable and arcuate movement, a rotatable table tilted at an angle 150 to said saw corresponding to the slope of the ring

slot, means on said table for receiving a plurality of rings, means for positioning the slot in said ring relative to said receiving means, means for advancing said table to move the ring adjacent to said saw, and means for moving said saw after each advancement of the table.

2. A ring re-sawing machine including, in combination, a saw suspended for rotatable and arcuate movement, a rotatable table tilted at an angle to said saw corresponding to the slope of the ring slot, a plurality of ring receiving elements on said table, means for positioning the ring slots relative to said receiving elements and means for withdrawing said positioning means before advancing said saw through said slot.

3. A ring re-sawing machine, including, in combination, a saw mounted for rotational and advancing movements, a rotatable table tilted at an angle to said saw corresponding to the slope of the ring slot, a plurality of ring sizing elements disposed on said top, a loading point adjacent to said table at which a ring is disposed in one of said receiving means, a retrievable tongue positioned to locate the slot of the ring relative to the table, means for retrieving said tongue, clamping means adjacent to said saw for expanding the ring in said sizing element, means for advancing and retracting said saw through said slot, means for releasing said clamping element, and means for advancing the table thereafter.

4. A ring re-sawing machine including, in combination, a saw suspended for rotatable and arcuate movement, a rotatable table tilted at an angle to said saw corresponding to the slope of the ring slot, means on said table for receiving a plurality of rings, fluid actuated clamping means disposed adjacent to said saw for clamping the ring in said receiving means, means for advancing said saw through said slot in the ring, and cam means for withdrawing said saw from said slot and for controlling the flow of fluid to said head for releasing the clamping means after the sawing operation.

5. A ring re-sawing machine including, in combination, a saw suspended for rotatable and

arcuate movement, a rotatable table tilted at an angle to said saw corresponding to the slope of the ring slot, means on said table for receiving a plurality of rings, fluid actuated clamping means disposed adjacent to said saw for clamping the ring in said receiving means, means for advancing said saw through the slot in the ring, cam means for withdrawing said saw from said slot and for controlling the flow of fluid to said clamping means effecting its release, and means for raising said ring from said receiving means thereafter.

6. A ring re-sawing machine including, in combination, a saw suspended for rotatable and arcuate movement, a rotatable table tilted at an angle to said saw corresponding to the slope of said ring slot, means for rotating said table, means for locking said table at predetermined points, a plurality of means on said table for receiving the rings, a retrievable tongue extensible into the slot of the ring at the loading position of the table, means for retrieving said tongue and for clamping the ring thereafter adjacent to said saw, means for advancing and retrieving said saw to machine the slot to accurate dimensions, and means for unlocking said table and advancing it a predetermined amount to position another ring adjacent the saw and for again locking the table.

7. A ring re-sawing machine including, in combination, a saw suspended for rotatable and arcuate movement, a rotatable table tilted at an angle to said saw corresponding to the slope of the ring slot, points about said table which include a loading point, a sawing point and an unloading point, a movable tongue projecting into the slot of the ring at the loading point of the station, means for retrieving said tongue during advancement of the table to the sawing position, a clamp for securing said ring during the sawing operation, means for releasing said clamp before the next advancement of said table, and means for raising said ring when positioned adjacent to the unloading point.
